GARMENT CLOSURE

Marguerite McFarlane, New York, N. Y.

Application September 27, 1941, Serial No. 412,573

4 Claims. (Cl. 2-38)

This invention relates to garment closures, and more particularly to the type of garment closure where a slide fastener is used and the garment is under some strain or tension.

An object of the invention is to provide a closure in which the edges of the opening may be easily brought together to enable the free movement of a slide fastener.

A further object of the invention is to provide a closure with which temporary relief from the binding effect of the garment may be secured by operation through the outer garments.

A further object of the invention is to provide a relief opening in a corset, girdle or similar garment, which may be opened and closed by the wearer without lifting or removing the outer garments.

It is well known that many garments of the supporting type, such as corsets, girdles and foundation garments, are designed to sheath and mold the body when the wearer is in a standing position. Also, many garments are designed to reduce excess flesh and are for that purpose very snug and confining about the hips and thighs. When the wearer sits for a period of time, such as in a theater or in an office chair, the effect of the garment is to unnecessarily and uncomfortably confine the thighs and hips and to cut down on the free circulation of the blood. Moreover, the continued wearing of such a garment causes an undesirable distribution of the flesh and defeats the general purpose for which the garment is designed.

While my closure is designed for, and adaptable to, any type of closure, it is particularly suitable for garments of the type just described, to enable the wearer to release the pressure in the lower portion of the garment through the outer clothing when the wearer is in a sitting position or when the garment becomes uncomfortably tight. Since under such circumstances the ordinary slide fastener cannot be closed without pinching of the flesh or obvious pulling and struggling with the fastener, my invention contemplates and provides additional means for bringing the edges of the slide fastener together so that the fastener may be closed by a simple quick movement. It further provides means to protect the wearer from being pinched or cut by the fastener during its operation.

In addition to the foregoing, my invention makes possible the release of pressure on the lower part of the garment when the garment is being put on or taken off and thus decreases the strain on the garment due to excess stretching

with the resultant straining of seams and loss of shape.

Other objects and advantages will become apparent as the description proceeds.

5 In the drawing—

Fig. 1 is a perspective view of a garment on a wearer embodying my invention;

Fig. 2 is a perspective view illustrating how the closure may be opened through the outer clothing;

10 Fig. 3 is a detailed view partly in section showing the structure of my closure in closed position;

Fig. 4 is a detailed view with the outer part of the garment partly broken away showing the closure in open position;

Fig. 5 is a cross-sectional view taken on the line 5—5 of Fig. 3;

Fig. 6 is a cross-sectional view taken on the line 6—6 of Fig. 3;

20 Fig. 7 is a cross-sectional view of a modified form in which the outer fabric of the garment is extended to cover the slide fastener.

As previously stated, my closure is adaptable to any slide fastener construction where tension is needed to bring the edges of the slide fastener together before the slide is closed. While I have shown my invention as applied to an undergarment, it will be appreciated that it is equally applicable to any number of constructions.

25 30 In the particular use shown, a girdle or corset 10 is provided with one or more openings 11 adjacent the front of the hip and thigh portion of the garment below the waist, which openings may be inserted in the seam 12 or at any convenient place.

The opening is adapted to be closed by a conventional slide fastener having the usual teeth 13 and slide 14. I have found that the fastener is most easily operated if the slide is provided with a fairly large flat ring 15 of sufficient circumference to allow the insertion of the thumb, and it is advisable to have the loop 16 sufficiently large to allow the free reversal of the ring 15.

35 40 The slide fastener unit may be of the conventional type having zipper backings 17 and 18 for the teeth 13, which backings may be fastened by the seams 19 and 20 to the edges of the opening 11. In order to prevent the catching of the flesh and to further enable the easy operation of the closure, a shield member 21 is stitched to the garment at one end 22, preferably the forward or front-most end of the opening.

45 50 55 The shield 21 extends under the zipper backings 17 and 18 and under the edge of the garment. At its far edge 23 the shield 21 is free but is main-

tained in position by the elastic stays 24 and 25. The stay 24 is fastened at 26 to the upper edge of the shield 21 and at 27 to the fabric of the garment. The stay 25 is fastened at one edge 28 to the shield some distance from the edge, and is fastened to the garment at 29.

A loop 30 on the edge of the shield 21 is provided to position the stay and shield and to allow the stay to stretch. A pull cord 35 extends from a point 36 between the shield and the zipper backing 17 through sliding means 37, 38, 39 and 40, and is provided at its end with a knob or bead 41. An elastic cord or thread 42 tacked to the garment at 43 may be provided to prevent the bead 41 from hanging downwardly when the fastener is closed. The members 37, 38, 39 and 40 may be eyelets, pulleys, or any other type of sliding means which will allow the free passage of the cord 35.

It will be noted that the cord 35 extends under the slide supports 17 and 18 so that as the fastener is closed or opened the cord is protected from being caught in the fastener. It will also be noted that the shield 21 lies between the cord 35 and the body and that the shield 21 always separates the fastener and its backing from the body.

From the foregoing description it will be readily appreciated that a woman may grasp the ring 15 through a dress and other outer or under garments and move the slide 14 upwardly to open the closure. This will naturally release the pressure and tension on the thighs and lower hips. When it is desired to close the opening this may be done by a simple one-two motion in which the bead 41 is grasped through the dress and other garments and pulled downwardly to bring the edges of the slide fastener together, while with the thumb of the other hand engaging the ring 15 the slide 14 may be pushed downwardly to affect a closure. The bead is then released and the elastic cord 42 will lift the bead out of the way.

In the modified form shown in Fig. 7, the edges 58 and 59 of the outer fabric of the garment are extended so as to conceal the zipper opening and the zipper supports 17 and 18.

While I have shown, in Fig. 1, a garment in which two relief openings are provided, the number of openings will be controlled by the nature of the garment and the function which it is intended to perform. Where a heavily reinforced garment is used, which tends to drastically restrict the body, two such openings would be indicated. Where a light girdle type of garment is involved, one such opening would be sufficient. The opening may be placed in any convenient position but I have found that it is preferably placed toward the front of the thigh where it is generally out

of the way and where it may be operated by the wearer inconspicuously as she rises or sits.

I claim:

1. The combination with a closure having a slide fastener, of independent means to bring the edges of said slide fastener together to enable the easy operation of the slide, said means comprising a cord fastened at one end adjacent the top of said closure and extending back and forth through sliding means whereby the pulling of said cord will bring the edges of said slide fastener into juxtaposition.

2. The combination with a closure having a slide fastener, of independent means to bring the edges of said slide fastener together and enable the easy operation of the slide, said means comprising a cord fastened at one end adjacent the top of said closure extending back and forth through sliding means whereby the pulling of said cord will bring the edges of said slide fastener into juxtaposition, and a shield positioned beneath said opening having one end fastened adjacent said slide fastener and extending beyond the opening at the other end.

3. In a garment of the corset type, means providing an elongated opening in the body of the garment substantially in the direction of its length, a slide fastener for normally closing said opening, a shield member positioned underneath said slide fastener, means for securing opposite edges of said shield member to the garment on opposite sides of said opening, said securing means including a pair of elastic members connecting one edge of the shield member to the garment and acting to maintain said shield in extended position under tension across said opening when the slide fastener is unfastened to permit expansion of the garment in the region of said opening.

4. In a garment of the corset type, means providing a relief opening extending upwardly from the lower edge of the garment, slide fastener means for normally closing said opening, a shield extending substantially the full length of said opening and having a greater lateral dimension than said opening when the slide fastener is unfastened, said shield being secured along one edge to the garment at one edge of said opening, and elastic means attached to the opposite edge of the shield and secured to the inside of the garment beyond the other edge of said opening for normally positioning the shield beneath the fastener means when said fastener means is fastened and for yieldably maintaining said shield under tension completely across said opening when the fastener means is unfastened to permit expansion of the garment in the region of said opening.

MARGUERITE McFARLANE.
